UNITED STATES PATENT OFFICE.

RALPH N. LOGAN, OF PHILADELPHIA, PENNSYLVANIA.

MACHINE FOR CLEANING SCALE FROM ANNEALED STEEL.

Application filed July 8, 1921. Serial No. 483,356.

To all whom it may concern:

Be it known that I, RALPH N. LOGAN, a citizen of the United States, and resident of Philadelphia, county of Philadelphia, and

5 State of Pennsylvania, have invented an Improvement in Machines for Cleaning Scale from Annealed Steel, of which the following is a specification.

The object of my invention is to provide 10 a machine especially adapted for cleaning the scale from annealed steel, and comprising vertically reciprocating baskets containing the steel to be treated and by means of which the steel is subjected to the action of 15 an acid bath; my improvements being more particularly directed to the special means and method employed for operating the baskets, whereby one man may efficiently handle a large quantity of material in a limited 20 time, resulting in economy in cost of treatment.

Heretofore, it has been customary to operate the baskets containing the steel to be treated by means of steam pressure, lifting 25 the baskets by the operation of a piston and cylinder mechanism and permitting the steam to exhaust into the room to lower the baskets into the acid bath after they have been fully raised, the vertical reciprocations 30 of the baskets being insured by repeated admissions of steam to the cylinder and its subsequent exhaustion into the room. That system has been found objectionable on account of the high cost involved and on account of the heating of the atmosphere of 35 the plant by the presence of the steam; and where the steam is exhausted into the room, the further objection by providing an objectionable humid atmosphere.

40 In putting my invention into practice, I dispense entirely with the use of steam for operating the baskets; employing compressed air for the purpose of raising and counter-balancing the baskets and loads and 45 a mechanical power means for depressing the baskets against the elasticity of the compressed air. More specifically, my invention comprehends a frame from which the baskets are hung, said frame being supported 50 upon an elastic cushion of compressed air by the employment of a piston and cylinder or equivalent means, the pressure of the air being just sufficient to conveniently cause the baskets with their load to rise clear of 55 the acid vats or tanks. Thereafter, the frame and the suspended baskets with their

loads are intermittently drawn downward against the elasticity of the compressed air by the mechanical means, the said operation overcoming the elasticity of the air in lowering the baskets and permitting the air to raise the frame and baskets on the lifting or upward action, whereby a minimum utilization of power is alone necessary.

60 My invention also consists of improvements hereinafter described whereby the above objects and results are attained, said improvements comprising certain organization and combination of parts which are fully described hereinafter and more particularly defined in the claims.

65 Referring to the drawings: Fig. 1 is a plan view of an apparatus embodying my invention; Fig. 2 is a side elevation of a portion of the same, more particularly showing the apparatus for raising and lowering the dipping cages; Fig. 3 is a cross section taken on line 3—3 of Fig. 2; Fig. 4 is a vertical section showing a portion of the compressed air cylinder and piston mechanism; 70 and Fig. 5 is an enlarged view of a detail of Fig. 2.

75 Referring more particularly to the machine for operating the dipping cages, the same consists of a vertical cylinder 2 having 80 therein a plunger 3 provided with a piston 3^a working in the cylinder 2 and subjected to the pressure of compressed air admitted by a pipe 27. The lower end of the plunger extends through a stuffing box 8 in the base 85 or pedestal portion 7 of the cylinder 2 (Fig. 4). The plunger 3, therefore, acts similar to the piston rod, but is made large in that it is required to sustain a large frame at its upper end from which the cages are hung. 90 Secured to the upper part of the plunger 3 is a horizontal wheel or circular part 4 having thereon radial pins 6 arranged circumferentially about the perimeter. Supported 95 above the wheel structure 4 are a series of radiating arms 5, and preferably five in number, though I do not restrict myself to the exact number, as my invention is applicable to the use of one or more cages and consequently to one or more of the said arms 5. 100 Depending from the outer ends of the arms 5 are chains 18 from which the cages 19 are conveniently detachable. The cages 19 may be made in any of the usual manners, such as being formed of open metal work of 105 intervening or perforated types to permit free circulation of the acid, to reach the 110

wheel contained in the cages and to be subjected to treatment. Arranged upon the floor and in properly spaced relation are a series of vats or tanks 20 in which the acid 5 is placed and into which the several cages are dipped and reciprocated therein vertically. As shown in Fig. 1, there are four of these vats 20, there being no vat under the lefthand cage 19, this being for the purpose 10 of providing a convenient space for removing a cage with the treated material from the suspending chains and for introducing a new cage with its contents. In the particular apparatus shown, it will, therefore, be seen 15 that there will be four cages subjected to the dipping process and when these cages are raised sufficiently clear of the tanks or vats 20, the sustaining frame and plunger may be rotated in transferring the cages to a 20 position for detachment or for successive treatments in each of the vats before the final removal, as may be desired.

When the cages and their supporting means are adjusted to a dipping position, the 25 following mechanical means is employed for imparting a reciprocating motion against the elastic pressure of the compressed air which counter-balances the weight of the sustaining frame as well as the dipping 30 cages and their loads. At each side of the base of the cylinder 2 is arranged a crank wheel 9 having a shaft journalled in bearings 10, said crank wheel operating an upwardly extending connecting rod 15 having 35 at its upper end a jaw 17 adapted to engage one of the radial pins 6 of the wheel 4. The jaw 17 of the connecting rod 15 is provided with a spring latch 18 which insures disconnection of the jaw from the pin 6 when 40 properly connected thereto, as will be understood by reference to Fig. 5. A chain 19 is provided for withdrawing the latch 18 when it is desired to disconnect the jaw 17 of the connecting rod 15 from the pin 6. 45 The two crank wheels 9 are provided with gear teeth on their perimeters which mesh with pinions 12 on the transverse shaft 11, the latter supported in bearings 14 and by which the said crank wheels 9 are rotated 50 in unison. The shaft 11 is driven by an electric motor 13 through gearing 16. By this means, the crank wheels 9 may be slowly rotated, raising and lowering the connecting rods 15, and which, by their connection 55 with the pins 6 of the wheel 4 on the top of the plunger 3, the said plunger and the frames 5 are caused to be reciprocated. As the compressed air supplied to the cylinder 2 below the piston 3^a is sufficient to nicely counterbalance the weight of the operating parts, it is manifest that a relatively small power for operating the crank wheel 9 is all that will be necessary, and consequently the cost of operating the machine is 60 relatively low. The amount of power to re-

ciprocate the cages vertically is substantially the same under all conditions of load, because the counter-balancing being performed by the compressed air, it is only necessary to vary the air compression to 70 suit any variable loads and when such loads are counter-balanced, the amount of power required for the reciprocation is substantially the same under all conditions of operation.

When the dipping operation has been completed and it is desired to lift the cages entirely clear of the tanks, the jaws 17 are disconnected from the pins 6 and are swung backward to rest upon supports 29. Increased air pressure is then supplied to the cylinder 2, and the plunger together with the cages are lifted to the maximum height, so that the cages are clear of the tanks or vats. Under this condition, the cages together with their supporting means may be rotated about the vertical axis of the plunger to the new position desired, and thereupon the air pressure may be lowered to permit the descent of the cages and the supporting means and whereupon the connecting rods 15 are again brought into engagement with radial pins 6, and upon putting the electric motor 13 into action, the vertical reciprocating movements of the cages 95 are again insured.

Referring now to the means for supplying the compressed air to the cylinder and plunger, the ordinary compressed air from any suitable source in the factory may be supplied by the shop line 22 and by means of the pipe 27 be supplied to the cylinder 2 of the dipping apparatus. The supply of compressed air from the shop line to the cylinder may be controlled by a valve B in the pipe 27. Between the valve B and the cylinder 2 and connecting with the pipe 27, is an expansion tank 28 which has a pipe connection 29 with said pipe 27, said pipe connection being provided with a control valve D. 10 When the dipping operation is being performed, the expansion tank 28 is in open communication with the cylinder and in that manner the air beneath the cylinder during the reciprocations of the piston and cylinder will be maintained substantially constant because of the relatively large cubic contents of the expansion tank. The use of the expansion tank enables a considerable vertical reciprocation of the piston 11 with a relatively small amount of power required of the electric motor 13, and therefore, this motor may be, as before stated, of a size only which is required to perform the reciprocating action irrespective of the 12 amount of load which is being handled, since the load is practically all counterbalanced by the compressed air.

25 is the accumulator tank and has a connection by a pipe 26 with the pipe 27 be- 13

tween the valve B and the cylinder 2, and said pipe 26 provided with a valve C for controlling the compressed air supplied from the accumulator tank to the cylinder 5 21 is a compressor or pressure booster and draws its supply of air by a pipe 23 connecting with the shop line 22, said pipe 23 being provided with a valve A to be opened only when the booster is to be put into 10 operation. The discharge port of the booster is connected by a pipe 24 with the accumulator tank 25. It will now be understood that the operation of the booster is to impress upon a portion of the compressed 15 air from the shop pipe 22 a higher pressure and deliver the air at this higher pressure into the accumulator tank 25, from which it may be delivered when required to the cylinder 2 of the dipping apparatus when 20 adjusting the air pressure to properly counter-balance the load of the dipping machine, or to raise the plunger for lifting the cages clear of the tank when they are to be shifted.

As compressed air does not condense, as 25 does steam, it is, therefore, capable of being used repeatedly and constitutes an ideal counter-balance capable of easy adjustment for a variable load. When a balanced condition has been secured at the upper stroke 30 of the piston, the vertical reciprocating motion can be accomplished mechanically with the expenditure of relatively small power. It will also be understood that, while the effect of the mechanical power will not only 35 be exerted both downwardly and upwardly (if in any manner resisted), the floating tendency of the dipping apparatus by reason of the elasticity of the compressed air may, if desired, be utilized to assist in the upward motion and to some extent relieve the mechanical power so that its work is exerted 40 more in depressing the cages and their supporting means than in elevating them. I prefer, however, that the counter-balancing 45 of the load by the compressed air shall be such that mechanical power operates as nearly uniform as possible, both in raising and lowering the cages, during the reciprocations. It will also be understood that the 50 extent to which the reduction in power may be carried while performing the work required will be largely dependent upon the volume capacity of the expansion tank 28, because the compressed air in the cylinder 55 must be discharged into the expansion tank when the cages are being lowered and should the expansion tank be too small, this air will be compressed to a high pressure, using the piston 3^a and cylinder 2 as a compressor 60 means, and such increase of the compression of the air would, to that extent, require more mechanical power to overcome it. By having a sufficiently large expansion tank relatively to the cubical capacity of the cylinder 65 2, below its piston, the variation in the air

pressure will be correspondingly slight, and in that event, the apparatus may be operated with a minimum amount of power for producing the reciprocations.

To operate the apparatus, the following 70 procedure would be in order: All of the valves A, B, C and D, should first be opened to allow the entire system to be filled with the ordinary air pressure from the shop line 22. Valves B and C are then closed, cutting 75 off the expansion tank and the dipping apparatus. The booster 21 is then put into operation and pumps air into the accumulator 25 at an increased pressure over that in the shop line and the maximum pressure 80 for the accumulator tank may be determined by any suitable control regulator 30 which shuts down the operation of the booster when the maximum pressure is reached. No description of this regulator will be necessary, as that is of ordinary construction. When the maximum pressure has been attained in the accumulator tank 25, the valves A and D are closed and the valve C is 85 opened, and compressed air at the higher 90 pressure of the accumulator is allowed to enter pipe 27 and cylinder 2 of the basket lifting apparatus until the top of the normal stroke of the piston is reached. Valve C is then closed, the links 15 of the mechanical 95 oscillator adjusted to the pin 6, and thereupon the motor 13 is started with the result that the cages and their supporting means will be reciprocated in the normal dipping operation. When it is desired to lift the 100 baskets to the extreme height, whereby they may be shifted clear of the tanks, when it is desired to load or unload them, the links 15 are disconnected, the valve D is closed and the valve C is opened, whereupon the accumulator 105 pressure is admitted to the cylinder 2 and raises the cages and supporting means to their maximum height. Valve C is then closed and the cages and their supporting means may be swung around to their desired 110 positions before again being lowered. To permit the cages to be again lowered to the normal dipping position of suspension, valve B is opened to allow the higher air pressure from the cylinder 2 to discharge back into 115 the shop pipe line and when the baskets have descended to the top of the normal stroke, the valve D is opened and thereupon valve B is closed and valve C opened sufficiently to permit air from the accumulator 25 to 120 enter the system in connection with the cylinder 2 to such an extent as will maintain the cages and their lifting means at the top of the normal stroke, thereupon the valve C is closed, the connecting rods 15 adjusted to 125 the pins, and proceed as before.

I have described my invention more particularly for use in machines or apparatus for cleaning scale from annealed steel, but I do not restrict myself to this use as the 130

same principle of apparatus may be employed for various industries, such as, for example, as dipping materials in textile operations, as dyeing, in which the materials 5 may be dipped into a tank containing a mordant, then into a tank containing a dye, and finally into one or more tanks containing washing water, by way of example. In fact, there are numerous possible uses for this 10 type of machine and my invention, therefore, resides in the construction, broadly considered, wherein the air pressure is utilized as counter-balance for the movable part of the apparatus and the load, while the actual reciprocating movements, whether rapid 15 or slow, are produced by the mechanical means. It is also to be understood that while I have shown a form of apparatus embodying a plurality of baskets and supporting means therefor, the invention may be used with a single basket equally well; and, moreover, while air is the natural medium to be employed, it is manifest that the substitution of a gas, such as carbonic acid or any 20 other permanent gas, may be substituted for air, if so desired.

I have described my improved method and means in that particularity which I deem to be the best exposition of my invention, and that which I prefer in commercial practice, but I do not restrict or confine myself to the minor or secondary details, as such are susceptible of modification, which may be resorted to as matters of mechanical 35 skill and without a departure from the spirit of the invention.

Having now described my invention, what I claim as new and desire to secure by Letters Patent, is:—

40 1. In a machine of the character stated, the combination of a frame adapted to be reciprocated, supporting means therefor, including a pneumatic counter-balancing means, a source of compressed air for making the pneumatic counter-balancing means effective, and mechanical power devices for reciprocating the frame while pneumatically counter-balanced.

2. The invention according to claim 1, 50 further characterized by means to vary the pressure of the compressed air, whereby the weight of the reciprocating frame and any load carried thereby may be accurately counter-balanced.

55 3. The invention according to claim 1, wherein further there is provided an expansion tank in communication with the source of compressed air, whereby the pneumati-

cally operated counter-balancing devices may be in communication with a cubical 60 space of relatively large capacity during the reciprocating movement of the frame.

4. The invention according to claim 3, further comprising an accumulator tank in controlled communication with the pneumatic counter-balancing means, and a booster device for supplying the accumulator with compressed air at a relatively higher pressure than that required in the expansion tank. 70

5. The invention according to claim 1, further characterized by having the reciprocating frame supported upon the top of a plunger, and a cylinder and piston mechanism for sustaining the plunger and supplied with the compressed air and depending devices from the vertically reciprocating frame for sustaining the load which is to be reciprocated. 75

6. The invention according to claim 1, 80 wherein the mechanical means for reciprocating the frame comprises a crank having a connecting rod extending to and jointed to the reciprocating frame, and a motor for rotating the crank. 85

7. The invention according to claim 6, wherein further the reciprocating frame is provided with a horizontally arranged pin and the connecting rod is provided with an adjustable jaw adapted to be locked in engagement with the pin. 90

8. The invention according to claim 6, 95 wherein further the reciprocating frame is sustained so as to be rotatable and provided with laterally projecting pins at intervals in the plane of its rotation, the said adjustable jaw of the connecting rod being adapted for attachment with any one of the series of projecting pins so that while the frame may be reciprocated by the connecting rod, the frame may be adjusted in a plane at right angles to the direction of reciprocation and put into connection with the connecting rod. 100

9. The invention according to claim 1, 105 wherein the means for mechanically reciprocating the frame comprises a pair of cranks, an electric motor gearing and shaft for simultaneously driving the two cranks at equal speeds, and connecting rods at one 110 end hinged to the cranks and at the other end hinged to the reciprocating frame for reciprocating it.

In testimony of which invention, I hereunto set my hand.

RALPH N. LOGAN.
